ABSTRACT: Hydraulic shears for continuous casting plants provided with a frame having knives mounted thereon and hydraulic cylinders mounted in succession actuating the knives. The frame is disposed with one end thereof on guide blocks pivoting on a bracket so as to move in a longitudinal direction along the guide blocks during cutting. The opposite end of the frame rests on a movable portion of a pivotally mounted hydraulic cylinder intended for counterweighting and oscillating the frame.

FIG. 8

HYDRAULIC SHEARS FOR CUTTING UP MOVING INGOTS

The present invention relates to hydraulic shears, and more particularly to hydraulic shears for continuous-casting plants.

Known in the prior art are hydraulic shears for continuous casting plants, provided with a frame having knives mounted thereon and hydraulic cylinders actuating said knives.

A disadvantage of said shears is that they have large overall width, which precludes their use on multimachine, multistrand plants for the continuous casting of metal.

An object of the present invention is to provide hydraulic shears which are small in width and capable of developing the required cutting forces.

In accordance with the above and other objects, hydraulic shears are provided having a frame with knives mounted thereon and hydraulic cylinders actuating said knives.

In conformity with the invention, the hydraulic cylinders actuating the knives are mounted in succession in at least one row. The frame is disposed with one end thereof on guide blocks pivoting on a bracket so as to be capable of moving in the longitudinal direction along the guide blocks before and during the process of cutting an ingot. The opposite end of the frame, with the knives mounted thereon, rests on a movable portion of a pivotally mounted hydraulic cylinder intended for counter weighting and lifting the shears.

It is preferred that at least one of the hydraulic cylinders is employed as a pressure intensifier.

The hydraulic shears according to the invention are small in overall width which allows a number of shears to be mounted in parallel with a minimum spacing between their axes which, in turn, allows the provision of multimachine strand multiplicants of the "strand machine" type for casting molten metal from ladles of medium and large capacity into ingots of small section.

The details of the present invention will become more fully apparent from a consideration of the following description of exemplary embodiments thereof, taken in conjunction with the accompanying drawings, in which:

FIG. 1 is an elevation view, partially in section of hydraulic shears according to the present invention;

FIG. 2 is a top view of the shears of FIG. 1;

FIG. 3 shows the shears as viewed along the arrow A of FIG. 2;

FIG. 4 is a cross-sectional view taken along the line III-III of FIG. 2;

FIG. 5 is an elevation view, partially in section, of hydraulic shears according to a second embodiment thereof;

FIG. 6 is a top view of the shears of FIG. 5;

FIG. 7 is a cross-sectional view taken on the line VII-VII of FIG. 5; and

FIG. 8 is a view of the shears in the direction of arrow B of FIG. 7.

The hydraulic shears comprise a frame 1 (FIGS. 1, 2) consisting of two side jaws 2 interconnected by crosspieces 3, 4, 5. The crosspiece 3 simultaneously functions as a support for knife 6.

Provided on the frame 1 is slide 7 movable along the jaws 2, and hydraulic cylinders 8 and 9 arranged in succession one after another and secured on the frame 1 by means of crosspieces 10.

It is also possible to arrange the hydraulic cylinders in several parallel rows.

A knife 11 is secured on the slide 7.

The rod of a piston 12 of the hydraulic cylinder 8 is connected to the slide 7 by means of an arrangement 13.

One working space of the hydraulic cylinder 9 is connected through a breather 14 to the surrounding atmosphere in order to prevent the formation of pressure or vacuum within this working space during the motion of piston. Said breather 14 simultaneously serves for draining leakages through the piston packings of the hydraulic cylinder 9.

Provided at one end of the frame 1 in the jaws 2 are slots 15 (FIG. 3) by the aid of which the frame is mounted on guide

blocks 16 (FIG. 3, 4). The guide blocks 16 are secured on axle 17 provided in bracket 18.

The opposite end of the knife-supporting frame is provided with ball-and-socket joint 19 (FIG. 1) which is employed for mounting the frame on the movable portion 20 of hydraulic cylinder 22 pivoting on bracket 21. The cylinder 22 is intended to counterweight and lift this end of the frame.

Such an arrangement of the frame makes it possible for the thrust knife 6 to move together with ingot 23.

10 To place the knife 11 into its initial position when the ingot size is to be changed, screw adjusting device 25 (FIG. 1, 2) is provided on the shank of piston 24 of the hydraulic cylinder 9, while for similar positioning of the knife 6, screw adjusting device 26 (FIG. 2, 4) is provided at the ends of the jaws 2 of the frame 1.

According to the second exemplary embodiment, one common body 27 (FIGS. 5 and 6) is provided in the hydraulic shears. Supported on this body is hydraulic cylinder 28 as formed by the body 27, piston 29, and piston rod 30, and pressure intensifier 31 as formed by the body 27, low-pressure piston 32, and high-pressure piston 33 interconnected by piston rod 34.

20 In order to prevent the development of pressure or vacuum within the low-pressure working space of the pressure intensifier 31 at its piston rod end when the piston 32 is moving, this space is connected to the surrounding atmosphere through breather 35.

To place the knife 11 into its initial position when the ingot size is to be changed, screw-adjusting device 36 (FIG. 5) is provided on the slide 7 while for a similar positioning of the knife 6 the screw-adjusting device 26, similar to that in the first embodiment of the shears, is arranged at the ends of the jaws 2 of the frame 1.

35 The operation of shears is accomplished in the following manner.

With the delivery of working liquid into the hydraulic cylinders 8 and 9, the rods of pistons 24 and 12 move the slide 7, with the knife 11 on it, to effect contact of the knife 11 with the ingot 23. Then the frame 1 along with the knife 6 begins to move on the guide blocks 16 until contact of the knife 6 with the ingot 23. Further on the cutting of ingot takes place by way of shifting its cut portion by the knife 11 while the knife 6 remains stationary in reference to the ingot 23.

40 Since in the course of cutting the ingot, the end of the frame 1 at the side of the knife 6 moves together with the ingot, the fixed position of the knife 6 in reference to the ingot 23 is ensured due to the movement of the frame 1 along the guide blocks 16, and to the pivoting thereof on the bracket 18.

50 Upon completing the cutting operation, the working spaces of the cylinders 8 and 9 which have been fed with working liquid, are now reversed to return lines whereas the working space at the side of rod of the piston 12 of the hydraulic cylinder 8 is reversed for delivering the working liquid into it. The working pressure displaces the rod of piston 12 of the hydraulic cylinder 8; the piston rod displaces the rod of piston 24 into the hydraulic cylinder 9 and shifts the slide 7, with the knife 11, on it into their initial position.

55 The operation of the shears in its second embodiment is carried out in the following way.

With the delivery of working liquid into the low-pressure working space of the pressure intensifier 31, the working space of the cylinder 28 at the end of the rod 30 is reversed to return lines whereas the liquid from the high-pressure working space of the pressure intensifier 31 is displaced by the piston 33 into the hydraulic cylinder 28 and shifts the piston 29 along with the piston rod 30 and the slide 7, together with the knife 11 mounted on the latter. The movement of the slide 7 is continued to effect contact of the knife 11 with the ingot 23. Then the frame 1, along with the knife 6, begins to move on the guide blocks 16 until contact of the knife 6 with the ingot 23.

70 75 The further operation of shears is accomplished in the same manner as that of shears in the first embodiment described above.

Upon completing the cutting operation, the low-pressure working space of the pressure intensifier 31 is reversed to return lines whereas the working space at the end of piston rod 30 of the hydraulic cylinder 28 is reversed for delivering the working liquid into it. The working liquid shifts the piston 29 of the hydraulic cylinder 28 and displaces the liquid out of it and into the high-pressure working space of the pressure intensifier 31. The liquid shifts the piston 33 of the high-pressure working space and also shifts the piston 32 via the piston rod 34 of the low-pressure working space of the pressure intensifier 31. Simultaneously with the piston rod 30 of the hydraulic cylinder 28, the slide 7, along with the knife 11, return to their initial position. As soon as the knife 11 is outside the confines of the ingot, the shears return to its initial position in the similar way as in the case of the first embodiment described above.

In the foregoing description of the embodiments of the invention, considered, a specific narrow terminology is employed for the sake of clarity; however the invention is not limited by the terms adopted and it should be understood that each of these terms embraces all the equivalent elements functioning in a similar manner and employed for solving the same problems.

The present invention is not limited to the exemplary embodiments set forth in the description, and there may be modifications within the scope of the following claims.

We claim:

1. Hydraulic shears for cutting moving ingots comprising a frame including opposite end portions, a bracket supporting one end portion of said frame such that said frame may undergo pivotal and reciprocating movements relative to said bracket, oscillating bearing means supporting the other end portion of said frame, said oscillating bearing means constituting counterweighing means and adapted for lifting said other end portion of said frame, a plurality of knives carried by said frame proximate said oscillating bearing means, one of said knives being fixed to said frame and another of said knives being shiftably supported relative to said frame, and a plurality of hydraulic cylinders supported in succession on said frame and operatively associated with one another to actuate said knives to cut said ingots.

2. Hydraulic shears according to claim 1, in which at least one hydraulic cylinder actuating the knives is constituted as a pressure intensifier.
